UNITED STATES PATENT OFFICE

157,727

REBOUND DEVICE FOR A BALL ROLLING
AMUSEMENT GAME

George R. Benak, Chicago, Ill.

Application December 21, 1948, Serial No. 150,297

Term of patent 14 years

(Cl. D34—5)

To all whom it may concern:

Be it known that I, George R. Benak, a citizen of the United States and a resident of Chicago, county of Cook, State of Illinois, have invented a new, original, and ornamental Design for a Rebound Device for a Ball Rolling Amusement Game, of which the following is a specification, reference being had to the accompanying drawing forming a part thereof.

Fig. 1 is a perspective view of a rebound device for a ball rolling amusement game embodying my new design;

Fig. 2 is an elevational view of the same;

Fig. 3 is a bottom plan view of the same.

The characteristic features of my design reside in the portions shown by means of full lines in the drawing.

This application is a continuation-in-part of my copending application Serial No. D. 147,968, filed August 6, 1948, for a ball bumper, now abandoned.

I claim:

The ornamental design for a rebound device for a ball rolling amusement game, as shown, and described.

GEORGE R. BENAK.
